[57] CLAIM

The ornamental design for refill container for a liquid dispenser, as shown and described.

DESCRIPTION

FIG. 1 is a front elevational view of a refill container for a liquid dispenser showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a bottom plan view of a second modified embodiment;

FIG. 8 is a bottom plan view of a third modified embodiment;

FIG. 9 is a bottom plan view of a fourth modified embodiment;

FIG. 10 is a bottom plan view of a fifth modified embodiment;

FIG. 11 is a cross sectional view taken along line 11—11 of FIG. 3;

FIG. 12 is a fragmentary side elevational view of FIG. 7;

FIG. 13 is a fragmentary side elevational view of FIG. 8;

FIG. 14 is a fragmentary side elevational view of FIG. 9;

FIG. 15 is a fragmentary side elevational view of FIG. 10;

FIG. 16 is a cross-sectional view taken along line 16—16 of FIG. 12;

FIG. 17 is a cross-sectional view taken along line 17—17 of FIG. 13;

FIG. 18 is a cross-sectional view taken along line 18—18 of FIG. 15; and,

FIG. 19 is a cross sectional view taken along line 19—19 of FIG. 15.

The undisclosed portion of the embodiments represented in FIGS. 7—10 and 12—19 are identical to those shown in the first disclosed embodiment, FIGS. 1—6 and FIG. 11.
